UNITED STATES PATENT OFFICE.

FOLGER ADAM, OF JOLIET, ILLINOIS, ASSIGNOR TO ILLINOIS WIRE & MFG. CO., OF JOLIET, ILLINOIS, A CORPORATION OF ILLINOIS.

CORNCRIB AND THE LIKE.

1,388,013.

Specification of Letters Patent. Patented Aug. 16, 1921.

Application filed June 30, 1919. Serial No. 307,495.

To all whom it may concern:

Be it known that I, FOLGER ADAM, a citizen of the United States, and residing at Joliet, county of Will, and State of Illinois, have invented certain new and useful Improvements in Corncribs and the like, of which the following is a specification.

The present invention has to do with certain improvements in corn cribs and similar structures which are intended for holding corn and other like products. When the corn is stored in bulk, it has a tendency to ferment and otherwise change its composition, owing to the moisture contained within it, and it is therefore desirable, if such action is to be prevented, to thoroughly ventilate all portions of the mass or body of the corn. There have been in the past various corn cribs in use which were so constructed that the outer portion of the mass or bulk of the corn could be readily ventilated. Such a construction, for example, was one in which the crib itself was slotted or slatted so as to readily admit the air to the outer layers or portions of the bulk of corn. This air, however, would not penetrate to the central portion of the corn, and this latter would, therefore, soon deteriorate and the fermentation or deterioration would rapidly progress toward the outer layers.

The main object of the present invention is to provide a corn crib or the like of such construction that all portions of the material contained therein will be ventilated in a thorough and effective manner. Another object is to provide a very simple construction of crib and one which can be readily manufactured from materials in common use and of cheap cost and which are obtainable in practically all portions of the country. Other objects and uses of the invention will appear from a detailed description of the same, which consists in the features of construction and combinations of elements hereinafter described and claimed.

The single figure in the drawing shows in perspective view a corn crib embodying the features of the present invention, portions thereof being broken away so as to more clearly reveal the construction and manner of operation of the present invention.

The corn crib illustrated is built up from slatted fencing comprising longitudinally drawn wires and cross slats, which type of

fencing is readily procurable at almost any portion of the United States. The outer portion of the corn crib comprises a circular enclosure 1 built up from such fencing bent into circular form, and the height of this enclosure can be made as great as desired by adding sections one on top of the other, as shown in the drawing. In the construction illustrated, two layers 2 and 3 are shown. It will be observed that when additional sections are built up in this manner, it is possible to interweave the end portions of the slats, as shown in the figure, thereby correspondingly improving the connection between the sections and giving added strength and rigidity to the entire structure.

In order to ventilate the interior of the crib, the following construction is illustrated: a central vent 4 is provided extending vertically through the central portion of the crib and preferably having its outer end 5 at a somewhat greater elevation than the upper edge of the crib, so as to surely reach above the contained corn or other material. This vent is conveniently built up from slat fencing of the same type as that of which the outer enclosure is constructed, and it is to be observed that the vent may be built up from several superimposed sections in the same manner. It will be noticed, from an examination of the figure, that the vent comprises two and one-half sections, as compared to the two sections of height of the outer enclosure, whereby the vent extends some distance above the enclosure.

The air entering the lower end of the vent is enabled to pass out and diffuse through the entire central body portion of the mass of material. This it is enabled to do because of the slots between the slats. In order to facilitate the entrance of air into the lower portion of the vent, I prefer to set the entire crib on a platform 6 which is set a slight distance above the ground to provide the space 7, so that the air can enter through said space and thus reach the lower end of the vent, there being a suitable opening in the platform permitting the air to pass from the space beneath the platform to the lower end of the vent.

While I have in this specification mentioned the use of these features of the construction particularly in connection with corn cribs and the like, still it will be under-

2
stood that the cribs may be used for the storage of any desired material such as wheat and other forms of grain. Furthermore, while I have herein shown and described only a single embodiment of the features of my invention, being that in which the crib and vent are built up from slat fencing, still I do not limit myself to the use of this particularly except as I may do so in the claims.

10 I claim:

1. A crib for the purpose specified, comprising in combination a circular inclosure constructed of a plurality of superimposed sections of slat fencing, comprising parallel slats and cross stay wires each of said sections being circular form and having their adjoining slat ends interwoven and having their slots standing in a vertical position, a platform on which said inclosure is mounted, means for supporting said platform above the surface of the ground to provide a ventilation space thereunder, there being a vent opening through said platform and a vent extending upwardly through the central portion of the inclosure, said vent comprising a series of superimposed sections of slat fencing comprising parallel slats and cross stay wires and having their slots extending in a vertical direction, and the lower end of the vent being in communication with

the vent opening in the platform, for the purpose specified.

2. A crib for the purpose specified, comprising in combination a circular inclosure comprising a plurality of vertical separated slats, a platform on which said inclosure is mounted, means for supporting said platform above the ground on which it stands, there being a vent opening in said platform, and a vent extending upwardly through the central portion of the inclosure, said vent comprising a plurality of vertical separated slats having slots between them for the egress of air into the central portion of the inclosure and the lower end of the vent being in communication with the vent opening in the platform, for the purpose specified.

3. A crib for the purpose specified, comprising in combination an inclosure, comprising a plurality of vertical separated slats, a platform on which said inclosure is mounted, a vent extending upwardly through the central portion of the inclosure to an elevation greater than the inclosure, said vent having a plurality of vertical slotted openings and the lower end of the vent being in communication with the space beneath the platform, for the purpose specified.

FOLGER ADAM.
